UNITED STATES PATENT OFFICE.

JOHN H. ODENBRETT, OF CHICAGO, ILLINOIS.

CORSET.

SPECIFICATION forming part of Letters Patent No. 436,431, dated September 16, 1890.

Application filed June 3, 1890. Serial No. 354,121. (No model.)

To all whom it may concern:

Be it known that I, JOHN H. ODENBRETT, residing at Chicago, in the county of Cook and State of Illinois, and a citizen of the 5 United States, have invented a new and useful Improvement in Corsets, of which the following is a specification, reference being had to the accompanying drawings, in which—

Figure 1 is a front view, and Fig. 2 is a 10 rear view.

Corsets have heretofore been constructed with elastic sections or gores placed in various parts, and with stiff and corded pieces in other parts.

15 This invention relates to the above class of corsets, and its object is to provide an improved corset in which the elastic sections will be so arranged as to give proper expansion of the corset at the point where the expansion of the trunk of the body requires such elasticity or expansion in the corset, and in which the stiffened portion is so arranged in relation to the remainder of the corset as to firmly support or hold the parts of the 25 trunk of the body which are to be held or supported. I accomplish this object, as illustrated in the drawings, and as hereinafter described.

That which I claim as new will be pointed 30 out in the claims.

The corset consists of two sections, as usual, which sections are laced together at the rear, as shown in Fig. 2, and are joined together by the usual clasps in the front, as shown in 35 Fig. 1. As these sections are alike, I will describe one section only.

a represents the steel at the front.

b are boned or corded sections running upward, which at the top are busted or pressed 40 out, as at *c*, to form the bust of the corset.

d is an elastic section joined to the section *b* on one side, and on the other joined to section *e*. The elastic section *d* extends upwardly to a little above the waist-line, as shown in Fig. 1.

45 Above the section *d* is a stiff section *f*, extending from the elastic section *d* to the top of the corset. The sections *e* are made in the usual form and are provided with the usual stiffening material.

50 *g* is an elastic section joined on one side to the section or sections *e* and extending down

a little below the waist-line, as shown in Fig. 2. Section *g* is attached on the other side to an inelastic section *h*, extending the entire length of the corset.

55

i is a stiff section extending from the lower end of the elastic section *g* to the lower edge of the corset.

j is the usual lacing-section secured to the section *h*.

60

I make the elastic sections *d* and *g* of narrow straps of elastic webbing. These narrow straps can accordingly stretch independently of each other. The section *d* extends above the waist-line and the elastic section *g* extends below the waist-line, so that at the waist-line there are two elastic sections which give a large amount of expansion to the corset at the waist-line, where it is necessary. The section *d* at its upper end gives an elastic 65 action at the point over the heart, where elastic action is particularly important. The stiff section *f* above this elastic section *d* firmly supports the bust *c*, keeping the bust in proper form and supporting the breasts, as 70 is necessary to maintain the proper form.

The elastic sections *d* of the two sections of the corset at their lower ends give a large amount of elasticity to the steels *a* and sections *b* at their lower ends, where they 75 support the abdomen. The corset must be laced fairly tight to give the proper form at the lower portion. The two elastic sections *d* at their lower ends give a large amount of elasticity to the corset at the abdomen, where a

large amount is particularly desirable on account of the swell of the abdomen. The elastic section *g* gives an elastic action to the corset over the shoulder-blade. This is important to give freedom of movement. The 80

lower portion of the section *g* extends below the waist-line, as above described, and its lower end is over the kidney. The elastic 85 action over the kidney is an exceedingly important feature, as an inelastic corset over

the kidney causes various diseases. The stiff section *i* comes back of the hip, thereby giving the proper form to that part, and also giving a perfect support to the upper parts 90 of the corset which support the trunk.

95 The corset above described accordingly gives an elastic action over the points of the 100

- body where expansion or elasticity is necessary, and it also gives a firm support where such support is necessary or desired. The elastic sections *e* and *g* at the waist-line give 5 a sufficient amount of elastic action to permit easy breathing. The elastic sections *g* give elastic action at the upper part of the corset at the rear in the region of the lungs, giving ease in breathing.
- 10 I am aware that elastic sections have been used extending in sections the entire length of the corset and in darts placed at various points, and I therefore do not broadly claim the use of elastic sections; but
- 15 What I claim as my invention, and desire to secure by Letters Patent, is—
1. A corset composed of inelastic sections *b* at the front, elastic sections *d*, extending from the bottom of the corset upward above 20 the waist-line, stiff sections *f*, extending from the sections *d* to the top of the corset, inelastic sections *e*, extending from the bottom of the corset over the hip to the top of the corset, and sections completing the back of 25 the corset, said elastic sections *d* being located midway between the hip-sections *e* and the inelastic front sections *b*, substantially as specified.
  2. A corset composed of inelastic sections 30 *h* at the back, elastic sections *g*, extending

from the top of the corset downwardly below the waist-line, over the shoulder-blade, inelastic sections *i*, extending from sections *g* to the lower edge of the corset, hip-sections *e*, extending from the bottom to the top of the 35 corset, and sections completing the front of the corset, said elastic sections *g* being midway between the back of the corset and the hip-sections of the corset, substantially as specified.

3. A corset composed of the inelastic sections *b* at the front and elastic sections *d*, adjoining the sections *b* and extending from the bottom of the corset upward above the waist-line, a stiff section *f* above the sections 40 *d*, extending to the top of the corset, inelastic sections *e*, adjoining the sections *d* and *f* and extending from the bottom to the top of the corset, and elastic section *g*, adjoining the section *e* and extending from the top of the 45 corset downward below the waist-line, a stiff section *i*, extending from the elastic section *g* to the bottom of the corset, and sections *h* and *j* at the back, substantially as and for the purposes specified.

JOHN H. ODENBRETT.
